UNITED STATES PATENT OFFICE.

LEWIS NATHANIEL HAINES AND ELMER IRWIN, OF KLAMATH FALLS, OREGON.

PRINT DRIER.

Application filed November 13, 1924. Serial No. 749,729.

To all whom it may concern:

Be it known that we, LEWIS NATHANIEL HAINES and ELMER IRWIN, citizens of the United States, residing at Klamath Falls; in the county of Klamath, State of Oregon, have invented certain new and useful Improvements in Print Driers; and we do hereby declare the following to be a full, clear, and exact description of the invention, such 10 as will enable others skilled in the art to which it appertains to make and use the same.

This invention relates to new and useful improvements in drying devices, and particularly devices for drying photographic prints, negatives, or the like.

One object of the invention is to provide a device of this character whereby the prints will be more effectively and quickly dried 20 than with devices of this character heretofore.

Another object is to provide a device of this character by means of which the prints will be flat when dried, the ordinary curling thereof, toward the film face, being obviated.

Other objects and advantages will be apparent from the following description when taken in connection with the accompanying drawing.

30 In the drawing:

Figure 1 is a front elevation of the device.

Figure 2 is a side elevation of the device.

Figure 3 is a vertical sectional view on the line 3-3 of Figure 2.

35 Referring particularly to the accompanying drawing, there is shown a comparatively shallow cylindrical casing 10, and connected to the lower side of the casing, and communicating therewith, is a rectangular box 11, in which is disposed the heating element 12, which may be the electric heating coils shown, or other suitable means. A cover 13 is removably engaged on the open side of the casing, and has a depending portion 14 engaging with the box 11, said cover having a central opening 15, straddled by the handle 16. Fixed to the center of the outer face of the other wall of the casing is a bearing 17, and rotatably supported in this bearing is 40 the shaft 18. On the outer end of the shaft is a belt wheel 19, for receiving power from any suitable source. On the rear wall of the casing, and secured to said bearing, is a depending clamp 20 which is adapted to be se-

cured to the edge of a table, bench, or other 55 suitable support, for holding the casing in proper upright position.

Secured to the shaft 18, within the casing, and radiating from the shaft, are the curved blades 21, and to the outer end of the concave face of each blade there is secured a transversely extending and slightly offset strip of metal 22, the purpose of which will presently appear herein. Secured to the outer ends of the blades 21, and forming the rim of the fan wheel, is a strip of wire screen 23, which is of the same width as that of the blades of the wheel.

In the side of the casing, just above the upper end of the box 11, is an opening 24, 70 which is controlled by the hinged door 25. Carried by the outer face of the door, and extending at right angles therefrom, is a notched arm 26, on which is slidably arranged a weight 27. This door is adapted 75 to be blown open, by the blast of air from the fan, as said fan rotates, to permit the escape of the excess of air, the weight being adapted to regulate the degree of pressure at which the door will open.

80 The normal tendency of a drying print is to curl toward the film side or face of the paper, thus rendering the handling of the prints difficult. If, when the prints are wet, the film sides are placed against the polished surface of a sheet of glass, enameled metal, or the like, no curl, to any appreciable extent, will be present in the dried print.

85 In the present device a number of longitudinally curved plates 28 are arranged to slip between the blades of the fan, in such manner that one end of each plate is engaged beneath the strip 22, and the other end engaged within the angle between adjacent blades. To the concave face of this 90 plate is applied the film face of the wet print, and the plate slipped into its place between an adjacent pair of blades of the fan wheel.

95 The source of heat being in operation, the 100 fan wheel is rotated, and as the fan blades pass across the open top of the box 11, they scoop up a quantity of hot air, from the box, which air is evenly distributed over the print between the blades. The prints having 105 been properly dried, the plates 28 are removed from the fan and the prints stripped from said plates. The prints will

have no tendency to curl toward the film faces thereof.

While we have shown the fan wheel driven by a belt, it will be understood that 5 a motor may be connected directly to the shaft of the fan.

In the bottom of the box 11 are formed 10 a plurality of openings 29, and pivoted on said bottom, in position to be swung into and out of covering relation to the openings, are the plates or doors 30, such construction permitting excess heat being forced, by the fan, out of said openings, thereby preventing too great heat on the 15 prints.

What is claimed is:

1. A print drier including a casing, a fan in the casing, a heating means mounted in position to discharge into the casing, 20 and wet print holding means removably mounted on the fan.

2. A print drier including a casing, a rotatable fan in the casing having blades mounted in the casing, a receptacle disposed below and communicating with the casing, a heating means in the receptacle, 25

and wet print holders removably mounted on the blades of the fan.

3. A print drier including a casing, a fan wheel mounted to rotate in the casing 30 and having commonly curved blades, a receptacle connected to the lower portion of the casing and opening thereinto, a reticulated rim on the fan wheel, and curved plates for holding wet prints detachably 35 engaged with the inner and outer ends of the blades.

4. A print drier including a casing, a fan wheel in the casing, said fan wheel including radial curved blades, offset transverse strips secured to the outer ends of the said blades, and wet print holding curved plates disposed between adjacent pairs of blades and each having an end engaged within the inner angle between blades and 40 its outer end engaged beneath a transverse strip.

In testimony whereof, we affix our signatures.

ELMER IRWIN.
LEWIS NATHANIEL HAINES.
